DESIGN FOR A CONTAINER POURING DEVICE

Walter S. Grant, Warren, Ohio, assignor to The
Ohio Corrugating Company, Warren, Ohio, a
corporation of Ohio

Application November 15, 1940, Serial No. 96,606

Term of patent 3½ years

To all whom it may concern:

Be it known that I, Walter S. Grant, a citizen of the United States, residing at Warren, in the county of Trumbull and State of Ohio, have invented a new, original, and ornamental Design for Container Pouring Device, of which the following is a specification, reference being had to the accompanying drawing, forming a part thereof.

Fig. 1 is a plan view of a container pouring device showing my new design;

Fig. 2 is a side elevation;

Fig. 3 is a front elevation; and

Fig. 4 is a bottom plan.

I claim:

The ornamental design for a container pouring device, as shown.

WALTER S. GRANT.
